DESIGN FOR A COMBINED ASH TRAY AND SAUCER

Oren C. Tweet, Astoria, Oreg.

Application October 29, 1946, Serial No. 134,355

Term of patent 7 years

(Cl. D44—10)

To all whom it may concern:

Be it known that I, Oren C. Tweet, a citizen of the United States, residing at Astoria, in the county of Clatsop and State of Oregon, have invented a new, original, and ornamental Design for a Combined Ash Tray and Saucer, of which the following is a specification, reference being had to the accompanying drawing, forming a part thereof.

Figure 1 is a perspective view of a combination ash tray and saucer, showing my new design;

Figure 2 is a sectional view taken along the line 2—2 of Figure 1;

Figure 3 is a bottom view thereof.

I claim:

The ornamental design for a combined ash tray and saucer, as shown.

OREN C. TWEET.
